UNITED STATES PATENT OFFICE.

GABRIEL BOURCIER, OF ERITH, ENGLAND, ASSIGNOR TO VICKERS LIMITED, OF
WESTMINSTER, ENGLAND.

INTERNAL-COMBUSTION ENGINE.

1,100,347.

Specification of Letters Patent. Patented June 16, 1914.

Application filed April 19, 1913. Serial No. 762,226.

To all whom it may concern:

Be it known that I, GABRIEL BOURCIER, a citizen of the Republic of France, residing at Erith Works, Erith, in the county of Kent, England, have invented certain new and useful Improvements in or Relating to Internal-Combustion Engines, of which the following is a specification.

This invention relates to improvements in internal combustion engines, particularly those used for the propulsion of aerial craft.

According to my improvements the operating surface of the cam used for actuating the valve mechanism is so shaped at the parts between the bosses or protuberances thereof (which are disposed in the usual manner at 120° apart) that by driving the cam in the reverse direction to and at a speed of one sixth that of the engine crank shaft it can be used to properly operate the inlet and exhaust valves of an engine comprising fourteen cylinders arranged radially in two rows of seven or by turning the cam over so that the back then becomes the front and driving it in the same direction as that of the crank shaft and at the same speed as before it can be used to properly operate the inlet and exhaust valves of an engine comprising ten cylinders arranged radially in two rows of five, without requiring to alter the contour of the cam operating surface. In order that the said improvements may be clearly understood and readily carried into effect the same will be described more fully with reference to the accompanying drawings, in which:

Figure 1 is a face view of the aforesaid cam. Fig. 2 is a vertical section showing the said cam applied to an engine having fourteen working cylinders disposed in two rows of seven. Fig. 3 is a similar view to Fig. 1 showing the said cam arranged for an engine having ten working cylinders disposed in two rows of five.

A is the cam which is driven by suitable gearing from the crank shaft B of the engine.

C C are the working cylinders extending radially from the engine casing C'. C' C' are the inlet and exhaust valves with which each cylinder is provided. These valves are in the example shown normally kept closed by springs c' c' and are moved inwardly to open them at the proper time

against the resistance of the springs, by 55 rocking levers C' pivotally connected at c' to rods C'. These rods are pivotally connected at c' to the tappet rods c' which extend through radial guides c on the engine casing C'. The said tappet rods have rollers 60 c' which are caused to bear continuously against the operating surface of the cam A by the action of helical springs c' surrounding the tappet rods. The said cam has on its operating surface three bosses or protuberances a situated in the same plane at 120° apart as aforesaid and the intervening surfaces between these bosses or protuberances are made in the form shown by Figs. 1 and 3. When the said cam is to be used 70 with a fourteen cylinder engine as in Fig. 2, it is driven from the crank shaft by toothed wheels b' b' of which the latter meshes with internal teeth c' on the said cam which is in the form of a ring detachably connected to 75 the portion that revolves on the antifriction balls of its bearing carried by a partition c' forming part of the engine casing C' in which partition the ball bearing for the adjacent end of the crank shaft is also mounted. The arrangement and ratio of the 80 gearing is such that the cam revolves in the opposite direction to that of the crank shaft and at one sixth of its speed. When the said cam is to be used with a ten cylinder engine it is turned over so that the back becomes the front and driven from the crank shaft by toothed wheels b' b' b' (see Fig. 3) of which the latter meshes with the internal teeth c' of the cam. The arrangement and 85 ratio of the gearing are such that the cam revolves in the same direction as that of the crank shaft and at one sixth of its speed. In any of the above stated applications of 90 the cam, the tappet rods will be disposed radially with respect to the cam and equidistantly with respect to each other; they will also all lie in the same plane. Any suitable gearing may be employed for driving the cam A so long as the said gearing 95 will impart to it the proper speed and direction of revolution relatively to the crank shaft.

What I claim as my invention and desire to secure by Letters Patent of the United States is:

In a multiple cylinder internal combustion engine the combination with the inlet

and exhaust valve mechanism, of an invertible and reversible cam provided with three protuberances disposed at 120° apart and having the operating surfaces thereof and the operating surfaces between the protuberances appropriately shaped to actuate the inlet and exhaust valves.

In testimony whereof I affix my signature in presence of two witnesses.

GABRIEL BOURCIER.
